UNITED STATES PATENT OFFICE.

ANTON MARTINUSEN AND JOHN W. STORFOLD, OF SEATTLE, WASHINGTON.

SOUNDING APPARATUS.

1,359,517.

Specification of Letters Patent. Patented Nov. 23, 1920.

Application filed July 21, 1916, Serial No. 110,555. Renewed April 30, 1920. Serial No. 378,017.

To all whom it may concern:

Be it known that we, ANTON MARTINUSEN, subject of the King of Norway, and JOHN W. STORFOLD, citizen of the United States of 5 America, residing at Seattle, Washington, have invented a certain new and useful Improvement in Sounding Apparatus, of which the following is a specification.

Our present invention relates to sounding 10 apparatus employed by mariners for ascertaining the depth of water or for bringing up specimens of bottom, said apparatus comprising a reel, line, and weight, and mechanism for controlling said reel.

15 The principal object of our invention is to provide sounding apparatus which will enable the operator to quickly pay out the line and quickly draw in the same, necessitating the attention of only one operator in 20 accomplishing the end in view.

Other objects of our invention are to provide sounding apparatus of the character described which is simple in construction, easily manipulated, substantial, and neat in 25 appearance.

Further objects of our invention will appear in the following detailed description, taken in connection with the accompanying drawings, forming a part of this specification, 30 and in which drawings:

Figure 1 is a central vertical sectional view through apparatus embodying our invention, parts being broken away to disclose details.

35 Fig. 2 is a sectional view on the line 2—2 of Fig. 1.

In the drawings, where similar characters refer to similar parts throughout the views, A designates a standard; B a reel revolvably 40 carried thereby, with a horizontal axis of rotation; C a line secured to said reel; D a weight at the free end of line C; E a hand-wheel; F motion-transmitting means operatively connecting wheel E and reel B to impart 45 movement of the former to the latter; G a device placing a normal drag upon means D; and, H a device for maintaining means F inoperative as motion-transmitting means so as to free reel B from operative 50 relation to wheel E.

Referring first to the standard A, it is 55 preferably constructed to provide a hollow 3 and in the example shown comprises a main body portion 4, provided with a flange 5 at its lower end, receiving bolts 6 by which the standard is secured to the deck; and, a

cap 7 mounted upon main body portion 4. The body 4 is provided with alined horizontal bores 8 serving as bearings, while the upper portion of the body 4 and lower portion of cap 7 is provided with bores 9 and 10 which are horizontally alined, and at the division line between body 4 and cap 7, these bores 9 and 10 serving as bearings.

The reel B may be of any suitable type 65 embodying a main body 11, cylindrical in shape, and flanges 12 secured to the ends thereof, the line C being secured to the body 11 in any suitable manner, so that the free end portion of the line depends from the 70 periphery of body 11, due to the weight D, and the force of gravity acting thereupon.

While we have herein shown a hand-wheel E for operating the apparatus manually, it is to be understood that this is merely by 75 way of example since a crank might be substituted therefor or other suitable devices adapted to impart movement to the motion-transmitting means F.

Said means may comprise a shaft 13 received by bearings 8, and supporting the reel B; a shaft 14 received by bearings 9 and 10, and supporting the wheel E, said shaft 14 being reciprocable longitudinally; and, in the example shown, provided with 85 an enlargement 15 in bearing 10, and providing a shoulder 16 for a purpose to be subsequently set forth; a gear wheel 17 rigid with shaft 13 internally of standard A; and, a co-meshing gear 18 within said standard. The gear 17 may be made rigid with shaft 13, as by collars 19 encircling said shaft and set-screws 20 turned tight against the shaft, while the gear 18 may be similarly secured to its shaft 14, as by collars 21 and 95 set-screws 22. The gear 18 is so mounted upon its respective shaft that, when the wheel E engages the standard A, said gear is in co-meshing relation with gear 17, however, if the shaft 14 is drawn, as by imparting movement to wheel E, to the position shown by dotted lines, the gear 18 is moved out of meshing relation to gear 17, which frees the reel B from wheel E, and the reel B is free to rotate due to the weight D acting upon line C.

In order to place the normal drag upon means F, the device G, in the example shown, said device being an expansion spring, is provided, said spring encircling 110 the shaft 14 and bearing against gear 18 at one of its collars 21, the other end portion

- of the spring abutting against a ring 23 engaging the internal portion of the wall of the standard, at bore 10. This spring has a tendency to retain the gears 17 and 18 in co-
meshing relation, however, by drawing upon the wheel E and moving the same to the position indicated by dotted lines, the spring G is considerably compressed. It is preferred to provide a spring G of such tension
10 that it will place a normal drag upon the motion-transmitting means F resisting casual rotation of drum B responsive to the force of gravity acting upon weight D and line C.
15 As to the device H, it may comprise a pin 24 adapted to extend through perforation 25 in standard A leading to bore 10; a chain, or other flexible member 26 secured to pin 24, and to the standard A as by screw eye
20 27. When the gears 17 and 18 are drawn out of co-meshing relation, as by moving shaft 14 longitudinally, said pin may drop downwardly engaging the shoulder 16, as indicated by dotted lines in Fig. 1, and the reel B is free to rotate as herein before set forth.
When bringing the apparatus into use, the operator has merely to place the weight D over deck, draw shaft 14 longitudinally un-
30 til the gears 17 and 18 are out of co-meshing relation, whereupon the reel B will rotate playing out the line C. When the weight D engages the bottom, pin 24 may be raised, whereupon the gear 18, responsive to spring
35 G moves into co-meshing relation to gear 17 and because of the normal drag of spring G

the drum B will cease to rotate, and it can be determined, by reference to line C, the depth of the water. In order to draw in line C, the wheel E is rotated, and it is preferred 40 to provide gear 18 of a diameter considerably greater than the diameter of gear 17 so that these two gears are speed-increasing when movement is imparted to wheel E.

Changes in details may be made without 45 departing from the spirit or scope of our invention; but,

We claim:

In sounding apparatus, the combination of a hollow standard, a wheel and reel, a 50 horizontal shaft supporting said reel from said standard, a longitudinally movable horizontal shaft supporting said wheel from said standard and provided with a shoulder, a gear rigid with said first shaft, a gear 55 rigid with said second shaft, said gear disposed in said hollow standard and adapted to co-mesh, or move out of co-meshing relation by movement of said second shaft, a pin adapted to be disposed in engagement with 60 the said shoulder of said second shaft to retain it with its gear out of meshing relation with the gear of the first shaft, and an expansion spring engaging the gear of said second shaft and compressed between said 65 gear and the wall of said standard, said spring encircling said second shaft and normally tending to force said second shaft to dispose said gears in co-meshing relation.

ANTON MARTINUSEN.
JOHN W. STORFOLD.
